UNITED STATES PATENT OFFICE.

FELIX KOCH, OF PITTSBURGH, PENNSYLVANIA, ASSIGNEE TO PRESSED STEEL CAR COMPANY, OF PITTSBURGH, PENNSYLVANIA, A CORPORATION OF NEW JERSEY.

ARTICULATED CAR.

Application filed February 3, 1926. Serial No. 35,687.

An object of the present invention is to provide a connection between the adjacent ends of adjacent car bodies of an articulated car, which will maintain these ends in their proper positions relative to each other and at the same time permit the bodies to swivel freely in all directions.

Another object of the invention is to provide the adjacent ends of adjacent underframes of an articulated car with a joint which will permit said underframes to swivel freely in all directions and yet prevent relative bodily sidewise or vertical movement between the ends of the underframes.

15 A further object of the invention is to provide a swivel connection between the adjacent bodies of an articulated car, which comprises a projection formed on the underframe of one body and a recess formed in the adjacent underframe adapted to receive said projection so that the bodies can swivel freely in all directions and at the same time will be prevented from moving vertically or sidewise relative to each other.

25 These and other objects will be apparent from the following description.

Referring to the drawings in which like reference characters refer to like parts, Fig. 1 is a plan view of the adjacent end portions of two adjacent bodies of an articulated car embodying the invention, the superstructure being omitted; Fig. 2 is a longitudinal sectional view of the same taken on the line 2—2 of Fig. 1, and Fig. 3 is a plan view similar to Fig. 1 but showing a modification of the invention, the floor plate being omitted.

Referring now in detail to the drawings, the reference character 1 indicates an articulated car unit which comprises a plurality of car bodies 2. In the accompanying drawings, the adjacent ends 3 of only two of such bodies have been illustrated, but it will be understood that an articulated car unit may comprise two or any other desired number of bodies 2. When the car unit comprises two bodies the adjacent ends 3 thereof are carried by a single truck 4, as shown in the drawings, and each of the outer ends of such bodies (not shown) is carried by a truck, thus a car unit of two bodies is carried by three trucks. When the car unit comprises more than two bodies, the outer ends of the bodies at opposite ends of the car are each carried by a truck and the opposite end of

each of these bodies, and the adjacent end of an adjacent body is carried by a single truck, thus a car unit of three bodies will be carried by four trucks. The truck 4 may be of any suitable form or construction and is preferably provided with a truck bolster 5. Intermediate its ends this bolster is provided with a truck center plate 6 having a concave upper bearing surface 7 which around its upper portion terminates in an upwardly extending circular flange 8. Each of the ends 3 of adjacent car bodies is provided with a member 9 which is suitably secured to the underframe of the car body and forms a portion thereof. Beyond the end of the car body this member is provided with an end wall 10 which extends on either side of the longitudinal center line at such an angle that when the adjacent ends of two of the bodies are suitably mounted on the truck, the walls 10 of the members 9 will not interfere with each other as the bodies swivel in passing around a curve. The outer end portion of this member 9 has a downwardly depending portion 11, the lower surface 12 of which is in the form of a portion of a sphere and is adapted to engage a portion of the upper surface 7 of the center plate member 6 secured to the truck, which surfaces 12 and 7 conform in contour with each other. The flange 8 of the truck center plate is adapted to engage with a vertically disposed portion 13 of the portion 11 of the member 9 to prevent the accidental separation of the body and the truck. Above the surface 12 and preferably near the top of one of the members 9, there is provided a projection 14 which extends outwardly from the end wall 10 and which at its outer end is in the form of a portion of a sphere. The other or adjacent member 9 has a recess 15 formed therein and in which the outer end portion of the projection 14 is adapted to extend, such recess being so shaped as to permit a free swiveling movement between the bodies and yet prevent any vertically or sidewise movement of the bodies relative to each other.

The surfaces 12 and 7 of the members 9 and center bearing members 6 respectively, are concentric with the outer surface of the projection 14 so that when the adjacent ends of two car bodies are in their proper operative positions, as illustrated in the drawings, the projection 14 on the end of one of the

bodies will extend into the recess 15 formed in the adjacent end of the adjacent body, and the surface 12 and 7 will be in sliding engagement with each other, there being a space 16 of varying width provided between the end walls 10 to permit free swiveling movement of one body relative to the other. It will here be noted that the connection between the car bodies and the truck is such that the projection 14, due to its engagement in the recess 15, will prevent the underframe of one of the bodies from rising above the underframe of the adjacent body or any other such bodily movement, and that it will permit free swiveling movement of the bodies relative to each other, and at the same time maintain the ends of the bodies in such positions relative to each other that the longitudinal center lines of the bodies will pass through the center of the connection at all times regardless of the angle one car assumes relative to the other.

It will be further noted that the projection 14 when in the recess 15, provides a means for transferring the buffing shocks from one to the other without having the walls 10 engage each other.

In Fig. 3 a modification of the invention has been illustrated in which the end of one body has secured thereto a separate member 17 having a recess 18 formed therein for the reception of the projection 14 formed integral with a separate member 19 secured to the adjacent end of an adjacent body. In this modification it will be noted that these members may be readily removed or replaced when desired without in any way interfering with the underframe or body center bearing members.

It will be apparent to those skilled in the art to which this invention appertains that changes may be made in the details of the invention without departing from the spirit and scope of the appended claims.

Having thus described the invention what I claim as new and desire to secure by Letters Patent is:—

1. In an articulated car comprising a plurality of car bodies, underframes for said bodies, and means for connecting the adjacent ends of adjacent underframes, said means comprising a spherical projection on one of said ends adapted to engage the other of said ends.

2. In an articulated car comprising a plurality of car bodies, underframes for said bodies, a projection on one of said underframes having an outer end portion of spherical form adapted to loosely engage the adjacent end of the adjacent underframe within a recess formed in the last mentioned underframe.

3. In an articulated car comprising a plurality of car bodies, the combination with the adjacent ends of the underframes of two ad-

jacent bodies, of a projection on one of said ends adapted to engage the adjacent end of the adjacent underframe, said projection being of spherical form.

4. In an articulated car comprising a plurality of car bodies, underframes for said bodies, body center bearings depending from the adjacent ends of adjacent underframes, a projection on one of said ends above one of said center bearings, the other of said ends having a recess formed therein above the other center bearing adapted to receive said projection.

5. A connection for the adjacent ends of two underframes of an articulated car, comprising body and truck center bearings, and a spherical projection on one of said underframes adapted to engage the other of said underframes above said center bearings.

6. A connection for the adjacent ends of two underframes of an articulated car, comprising a spherical projection on one of said ends adapted to loosely engage the other of said ends.

7. In an articulated car comprising a plurality of car bodies, a truck supporting the adjacent ends of two of said bodies, center bearing members on said bodies and truck adapted to cooperate to prevent longitudinal and transverse movement of said bodies relative to said truck and to each other, and means above said truck for preventing relative vertical movement between said ends, said means comprising a projection of spherical form on one of said ends adapted to engage the other of said ends.

8. In an articulated car comprising a plurality of car bodies, a truck supporting the adjacent ends of two of said bodies, said ends for their greater part being spaced apart, and a projection of spherical form on one of said ends adapted to engage the other of said ends for maintaining the spaced relationship between said ends.

9. In an articulated car comprising a plurality of car bodies, a truck for carrying the adjacent ends of two of said bodies, and means connecting said bodies, said means comprising a truck center bearing, a body center bearing on each of said ends adapted to engage said truck center bearing, a spherical projection on one of said ends adapted to engage with a curved bearing surface formed in the other of said ends, the bearing surfaces of said bearings and projections being concentric.

10. In an articulated car comprising a plurality of car bodies, a truck for supporting the adjacent ends of two of said bodies, a truck center plate on said truck, a body center plate on each of said ends adapted to cooperate with said truck center plate to prevent longitudinal movement of said bodies relative to said truck and to each other, a spherical projection on one of said ends

adapted to extend into a recess formed in the other of said ends to prevent vertical movement of said ends relative to each other, the connections between said ends and truck 5 permitting free swiveling movement of the bodies relative to each other and to the truck.

11. In an articulated car comprising a plurality of car bodies, a truck supporting the adjacent ends of two of said bodies, a truck center bearing on said truck, a body center bearing on each of said ends adapted to cooperate with said truck center bearing to permit swiveling movement between said 10 bodies and truck and to prevent longitudinal movement of said bodies away from each other, a projection on one of said ends adapted to engage the other of said ends to pre- 15

vent longitudinal movement of said bodies toward each other.

12. In an articulated car comprising a 20 plurality of car bodies, a truck supporting the adjacent ends of two of said bodies, a truck center bearing member, a body center bearing member for each of said bodies adapted to cooperate with said truck center bearing member, said body center bearing members being spaced apart and a projection on one of said ends adapted to engage the other of said ends to prevent said 25 body center bearing members from moving 30 into engagement with each other.

In testimony whereof I affix my signature.

FELIX KOCH.
